(57) **CLAIM**

The ornamental design for a microscope, as shown and described.

DESCRIPTION

FIG. 1 is a first perspective view of a microscope showing our new design;

FIG. 2 is a second perspective view of FIG. 1;

FIG. 3 is a top plan view of FIG. 1;

FIG. 4 is a bottom plan view of FIG. 1;

FIG. 5 is a right side elevational view of FIG. 1;

FIG. 6 is a left side elevational view of FIG. 1;

FIG. 7 is a first end elevational view of FIG. 1; and,

FIG. 8 is a second end elevational view of FIG. 1.

The dotted lines are intended to show features that are environmental only and form no part of the claimed design (for example and without limitation, the eyepiece ring and the zoom and focus controls form no part of the invention). Also, there is no intent to claim any surface indicia as all such surface lines are merely intended to be shading lines.
